US0D1015692S

(12) **United States Design Patent** (10) **Patent No.:** **US D1,015,692 S**
(45) **Date of Patent:** **** Feb. 27, 2024**

(54) **FOOTWEAR**

(71) Applicant: **Target Brands, Inc.**, Minneapolis, MN (US)

(72) Inventors: **Mariya Kroshinskaya**, Minneapolis, MN (US); **Olivia Hillard**, Minneapolis, MN (US)

(73) Assignee: **Target Brands, Inc.**, Minneapolis, MN (US)

(**) Term: **15 Years**

(21) Appl. No.: **29/891,179**

(22) Filed: **May 2, 2023**
